(57) **CLAIM**

The ornamental design for a portable fingerprint recognition apparatus, as shown and described.

DESCRIPTION

FIG. 1 is a perspective view of a portable fingerprint recognition apparatus showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a perspective view thereof in a condition that the upper cover thereof is opened upward and the inner window for recognition is exposed;

FIG. 9 is a front elevational view thereof in a condition that the upper cover is opened;

FIG. 10 is a rear elevational view thereof in a condition that the upper cover is opened;

FIG. 11 is a left side elevational view thereof in a condition that the upper cover is opened;

FIG. 12 is a right side elevational view thereof in a condition that the upper cover is opened;

FIG. 13 is a top plan view thereof in a condition that the upper cover is opened; and,

FIG. 14 is a bottom plan view thereof in a condition that the upper cover is opened.
